FIG. VII.

FIG. VIII.

FIG. IX.

FIG. X.

INVENTOR
Hermann F. Cuntz

UNITED STATES PATENT OFFICE

HERMANN F. CUNTZ, OF NEW YORK, N. Y.

AIRPORT

Application filed May 28, 1928, Serial No. 281,051. Renewed June 22, 1932.

This invention relates to landing fields for aircraft, but more particularly to airports or terminals for the accommodation of the landing and leaving of airplanes, and their accommodation for handling their loads of goods or passengers, for more desirable accommodation of planes when not in use but required to be accessible, for providing repair and overhaul space for airplanes when not in use at the airport, protection of goods or passengers when alighting or embarking, for accessibility for passengers or freight delivery adjacent the most adaptable part of the flying field for landing and hop-off, and for various other purposes and for the advantages as will hereinafter more particularly appear.

In general, the aim is to provide an airport which will have a minimum or no border obstructions to interfere with the airplane as it climbs at the start when rising from the ground, and still to have hangar space readily accessible for the protection of airplanes when not in use, to have overhauling and shop facilities where planes can be readily handled but without obstructing the flying field. While broadly this involves under-field-level hangars and shops and passenger accommodations, in some forms of the novel plans and arrangements mail planes may be loaded in quickest time by being adjacent trucks or trains with provision made for using their own power to rise to the level of the field for the hop-off, after passengers, mail, or other goods have been stowed under cover, and therefore the get-away is without the necessity of passengers or goods being handled in the open. In some features or forms of the invention underground buildings become directly accessible by under-field streets or roads or passageways, and a relatively small structure provides for the field surface requirements for the loading of the "flying stock" upon arrival and departure. In some forms it may be possible a central small station is the only surface projection above field-level with a clear field entirely surrounding it, or with the passenger handling facilities under the landing field level, and thereby provides, un-

der certain conditions, the best approach and departure for flying stock in every direction of the compass to meet the conditions of winds varying from every direction.

Coordinated with such facilities providing a practically clear field throughout, I may lay out adjunct facilities required about an airport, in ways that limit the height of any such structures above the flying field level, still providing entire accessibility to such additional buildings as the station, business offices, hotels, restaurants, as well as the shops or repair facilities, and the stations for supplies.

Among the various advantages that the coordinated layout provides are—the hop-off of flying stock without the necessity of climbing above any structures on the landing field border, the accommodation of passengers entirely off the field, or at least keeping all people off the field until passengers are required to embark or after they have alighted, avoiding all trucking or other vehicles passing over the field level except when actually servicing planes in use, most accessible delivery of supplies for all purposes at the field without running over the field, the particular advantages with respect to the drainage of the actual landing field area, thereby assuring better maintenance of field surface under all conditions of weather.

Among the particular results achieved are safety in operations particularly at airports or terminals for commercial operations, safety for the fliers, economizing in space and securing more permanency of good field conditions, as well as other results which will be apparent from the disclosures in this specification.

The use of any or all of the inventions herein set forth depends upon the particular site to be used for an airport or terminal. I select, if possible, a sufficiently large area which in its natural condition has an average level above the land beyond the border of the landing field. In some cases part of the required area at a natural elevation above adjacent land, and I extend that land by decking over additional contiguous land so that the space for hangars, repair shops and

the handling of road vehicles with goods or passengers, or trains, is below the decked portion. Such a combination of natural conditions to accommodate a layout or design 5 of port is more economical, and particularly I aim to select such a site where the major portion of the landing area has a minimum of cut and fill to bring it to the desired uniform level and smoothness and with a proper 10 condition of soil for drainage and for permanency of surface. With this a minor area at one or more sides of the lower level land provides for the decking to make the underground hangars and shops, etc., with a minimum 15 of cut and fill.

The meteorological conditions at any particular site determine the compass position of equipment with respect to the landing field, and the preferable direction of runways 20 and "dock" or the major and minor dimensions of the field. The underground or sub-hangar floor practically on the level of the road, and if possible the main road to be used for trucking of supplies and goods for 25 transportation and for servicing the machines for overhauling and repair, so that the personnel working in the sub-hangars and shops and all of their supplies at no time obstruct the actual landing field.

30 By having the field, or as much of it as possible above the level of adjacent land also prevents the visiting public from encroaching on the field to interfere with the operation of the airplanes. Also fencing to exclude the masses, or control access to the port can thus be installed on land below the level, so that even the top of the fencing is never above the field level.

On the whole, for usual purposes these 40 inventions are best embodied in layout and equipment of a site which is a natural plateau with a gradual sloping from the rim in all directions where the prevailing wind determines the direction of landing and hopping off. If possible the avoidance of any natural or artificial obstructions within less than a few thousand feet of the field adds to the 45 advantageous layout for flying conditions. Besides the relative elevation of field and 50 the border areas for sub-hangars and sub-shops, I select preferably an elevation with suitable draining soil that is always above any possible flood conditions in the locality, and thereby insure a condition of field for 55 landing in spite of any storms or floods, at all times.

As airports become more numerous, and different ones are provided for specific use for small or for large planes, conditions 60 served by a small field area will sometimes permit the creation of the landing surface entirely by decking over an area usable for other purposes, and in such cases the sub-hangars and shops are created as part of the 65 structure building to support the decking.

In any case, while elevators may be used to transfer the flying stock from the field to sub-hangar or shops, I prefer to provide ramps. Such ramps may be located on the margin of the field, and planes under their own power may be driven up the suitable grade provided. In other cases it becomes more advantageous to have the field end of the ramp covered by vertically swinging door or cover which in its closed position is entirely flush with the adjacent landing field surface. Such ramp doors may open by swinging above the field level, but I prefer to hinge them at the level of the field and open the access to the sub-hangars and shops by swinging the ramp cover down so that in its depressed position it constitutes the ramp at the proper incline, or at least part of the ramp. Suitable arrangements for field visibility from the sub-hangar insures opening 70 75 80 85 the ramp access only when no flying craft would be interfered with operating on the field, and safety equipment of the ramp doors are provided to prevent accidental operation and at all times insure the contiguous level 90 of the field, except when conditions are proper for the housing of the planes in the sub-hangars or feeding them on to the field.

As it will be understood that by far the major part of the time flying stock is inactive, and only a very small percentage of the time are the planes actually using the field, consequently the use of sub-hangars and sub-shops most advantageously accommodates the actual conditions of operations 95 100 at an airport.

The accompanying drawings show various embodiments of my invention that have been made in the actual plans or layouts in several 105 ports intended as major air terminals where traffic originates and stops, and which therefore require accommodations for storing, overhauling and repair of flying stock. This is to be distinguished from air stations where 110 planes mainly land for re-fueling en route, and also entirely distinct from emergency landing fields.

Fig. I is a plan view of a portion of an airport.

Fig. II is a vertical section of Fig. I on the line II-II.

Fig. III is a section on an enlarged scale with additional details, of the hub-hangar construction.

Fig. IV is a vertical section of an airplane dock combined with an underground station.

Fig. V is part section and part elevation showing coordinated control-building and quarters coordinated with dock and railroad station.

Fig. VI is a plan view of a central section of a landing field with underground access road.

Fig. VII is a section of Fig. VI, on line VII-VII.

Fig. VIII is a cross-section of the depressed road and deck, on line VIII—VIII of Fig VI, with height slightly exaggerated.

Fig. IX is a cross-section of Fig. VI, on line IX—IX, with height of sub-terrain station exaggerated.

Fig. X is a cross-section of the underground and field connections in Fig. VI, on line X—X.

10 In Figs. I, II and III, the landing field area 1, may be level or slightly dipping in directions according to preferred practice and to suit the particular service at the port, has a margin bordering a railroad 2 which is treated 75
15 in the planning and construction to accommodate sub-surface hangars. That is, for the purpose of what I have named sub-hangars, meaning the arrangement for airplane dead storage, or for overhauling space below the 80
20 surface of the landing field proper. In this arrangement a deck 3 is contiguous with the surface of field area 1, so that planes may run to the extreme edge, thereby increasing the available field area in addition to the 85
25 utility of the underground space. The deck has an abutment edge 4 and is supported by suitable columns 5 carrying girders 5^a. At the field end of the underground storage space 90
30 is a ramp or inclined plane 6, and for heavy planes certain of the ramps, as 6¹ may have a less steep angle,—in either case providing for quick transfer of planes from the landing field 1 to the floor of the hangars or shops. Such transfer would require only a few 95
35 minutes, and when no transfer is being made the opening for access to the ramp is covered by a door 7 pivoted at 8 with a counterweight 9, and suitable haul-down and elevating levers, or electric equipment provide for 100
40 quick opening or closing. This door 7 forms a flush surface when closed with the adjacent area, and is trussed and constructed so as to withstand the weight of any flying stock that may pass over it. Thus the access to the sub- 105
45 hangars or shops in no way interferes or detracts from the available useful space for landing and hop-off of airplanes on the field.

In the particular construction shown in these figures, the available port area was adjacent a railroad, and the tracks 2, or the plural tracks 2^a were on an embankment, so that by excavating the material to provide for the sub-hangars, it supplied spill to bring the adjacent field area up to the desired level of the deck over the hangars, and also to provide the field elevation such that leaving and landing the airplane would clear the railroad embankment, which also embodied the underground electric feeders 2^b, thus adapting the construction to fit the particular situation with the elimination of all obstructions above landing field level.

It also provided for additional trackage 2^d at a level below the floor of the sub-hangar 65 so that rail deliveries could be made on one

level directly under the hangars for loading on to planes in the hangars if desired, thus permitting the planes fully loaded and ready for flight to mount ramps to field level and proceed without delay or danger in stormy weather where field loading or discharging would be more difficult.

The sub-hangars are provided with skylights 10, which being on a slight slope of the deck automatically clear themselves of dust or snow, etc. In the form shown in Fig. III, the street 11, adjacent the railroad embankment, affords street vehicle access for supplies or freight directly to the sub-hangar without ever encroaching upon the landing field. In order that no ship may leave the sub-hangar, or that the ramp door be opened when any plane is moving in that vicinity on the field surface, a periscope 12 is arranged adjacent the abutment or parapet 4, so that the mirror 13 will be protected from collision of planes, and also providing a protection for weather, still permitting a reflected picture of the vicinity of the "trap-door" downward to a second mirror 14 and to a mirror or suitable screen 15,—directly visible to the man standing in the hangar and manipulating the raising and lowering tackle of the door.

In the embodiment shown in Figs. IV and V, the landing field area 1 is continued by a deck 16 at the same level across a cut containing railroad tracks, and the incline to the level for access to the railroad trains is a curved ramp 17, contiguous with the surface is a ramp door 18, hinged at 19, flush with the surface of the field with counterweight 19^a. The door 18 is trussed and constructed to provide support for the area of the field it closes for any load likely to roll over it, and when open a railing 20 is automatically thrown up to prevent accident and to indicate that the ramp door is open, or about to be opened. When it is closed the rail being collapsible on to the ground in suitable sockets to leave a flush surface, also throws a bolt or a series of bolts 21 under the edge of the door in order to firmly support it flush with the adjacent field area.

In this arrangement a site was selected where two-way tracks were at different levels and both below the adjacent natural land level, and with this plan of arrangement of the dock 22 for discharge from and embarkation in planes, the other characteristics of the field were provided in particular selecting the area of land though irregular in surface, in a manner that provided an average level that could be conditioned to a uniform field elevation to exactly suit the existing trackage. One-way track 23 provides for the delivery of passengers or mail, registers with the platform 24 so that the cargo, and particularly mail need be handled only once, namely, from train to plane, and under cover and complete protection. The plane is then

loaded and ready for flight, the ramp door 18 is opened, and under its own power the plane climbs the ramp on to the surface of the field. A drop-door 25 is provided in the abutment or wall, so that after loading the plane can be moved slightly, the door closed, and a reaction to the backwash of the propeller will, if it proves necessary, serve to aid the climb up the ramp.

- 10 Tracks 26-27 are for traffic in the opposite direction from 28, and land at the lower level platform 27, with ramps 28-29 for passenger and freight handling to the platform 24, while ramp 29 leads to stairs 30 entering 15 the ground floor of the passenger station, of which front steps 31 are shown forming the direct access to the dock 22.

In Fig. V, besides the detailed construction shown in Fig. IV, the passenger station or waiting-room 31 is a single story, and in particular is provided with a slightly domed roof, preferably with glass, wireglass if necessary, in order that the complete skyward vision is provided so that those awaiting arrival, or ready to depart in a plane, will have a full view of the plane's approach even though passing overhead, and will also enable all occupants of the building to at all times observe the air traffic. A roadway 32 at a lower level gives access to a lower story of the station 31, and also gives access to the hotel, restaurant or office building 33 which is on a still lower level, and in addition has access from its lower story to the road 34. Thus vehicular traffic on either of the roads is entirely remote from the landing field area. The hotel or office building 33 can be made by this arrangement as large as desired with several stories, and still not in any way interfere with the flying operations, and its roof 33^a is similar to roof 31^a of the station building and on the same level. This provides visibility in all weather when occupants of the restaurant or hotel cannot be outdoors on the terraces 33^b, 33^c, 33^d, which terraces are arranged for service in good weather, and are constructed on the set-back arrangement in order that the greatest possible area be provided for skyward vision, thereby to meet the requirements of the new transportation, namely, air traffic visibility, not alone for convenience, but in order that all concerned with the operations at the port may at all times orient themselves with respect to the going and coming of aircraft. This condition differs from the approach of railroad trains along a definite track, or vehicles along a definite road, and therefore provision is made to at all times see the sky in all directions because airplanes can approach the port from any direction of the compass.

In the construction shown in Figs. VI to X, a road 35 under the level of the landing field has a deck 36 suitably surfaced to meet the requirements of airplane landing. This

road preferably extends across the field, and may be straight or otherwise, but reaching a generally central point in the field where a small surface station and control-building 37 is the only protrusion above the level of the field. This station will be suitably illuminated and mark the centre of the field, so that at all times day or night planes can arrive in the wind and still be adjacent the control and receiving or departure depot. 75 From this surface station or control building suitable stairs and elevators run to the lower level, namely, the level of the underground street 35. As shown, the street diverges around the underground receiving 80 station 38 with one-way parts of the street 35'-35' affording convenient access to the lower story of the underground station.

For expeditious and safe handling of mail or other goods, the underground street provides access also, when desired, to a ramp 39, with a ramp door 40 so arranged that transfer of mail, etc., from road vehicles can be made direct to a plane, and the plane then closed and climb with its own power on to the field surface, and hop-off, after all loading or discharging has been done under cover and full protection.

As shown in the drawings, there are various details of construction that lend to the greater utility, safety and efficiency for control operation and handling of traffic at airports, than is the case in constructions of airports heretofore in use, or such as have been suggested prior to my invention. The observation-control structure has a clear visibility across the field for the obvious necessary purposes of the management of the port, but its domed roof, preferably in part or whole of glass, assures desired protection, at the same time visibility in all directions, in addition to the visibility of the occupants across the entire field. Making the roof or various roof portions curved or sloping insures their shedding snow readily, and permits the use of devices such as wipers to insure clear visibility at all times. The same applies to the roofs and protection over the terraces, etc., on the stations, with the stations preferably interconnected with the despatch building or the dock where passengers alight and embark.

The only structures that extend above the flying field level or the landing deck, are a minimum of obstruction to flight operations and still provide the necessary signal and communication station with least possible obstruction, and with a generally flush roof which is made of heavy construction, the occupants of the building are well protected and still have desired visibility, and the minimum of liability of aircraft collision with field structure is secured by such construction and arrangement.

Thus where the natural contour of topog-

raphy permits the airport has its landing area at a level, with only necessarily one structure for control and management on the surface, and for temporary use of passengers or the handling of mail. Even the handling of mail and passengers may be effected below ground, that is below the level of the landing area, and in such case suitable means as elevators carry the plane to the hop-off area, or, as shown, the plane may with its own power climb the surface by suitable inclined ways. For general housing of planes when not in use, the incline may run off the margin of the landing field, particularly in climates where weather protection of the incline or ramp is unnecessary.

Where the dock and control and traffic station are at one side of the landing area, the arrangement, in the case of suitable topography makes possible the approach by vehicles or even by railroads, not alone off the field but close to it accessible under cover directly to the field, while the adjacent structures and all their activities for passengers or supplies or freight are conducted at a lower level, and thereby in no way obstruct a plane leaving the field even though delayed in its climb after leaving the margin.

Where the conditions permit, the underground road across the field provides for accessibility at all times well protected, and the handling of passengers and goods below field level, so that no one and no material need reach the aircraft operating area except the management personnel and material immediately after discharge or immediately before embarkation. With such construction all planes coming or going can land immediately adjacent the control station for every direction of wind, thereafter they can taxi to other parts of the field preferably near the border where the sub-hangars approach on suitable signal from control station or pilot, opens the communication to the underground storage space where suitable tackle or pilot control of the craft permits ready transfer to the lower level,—whereafter the entire field level area is contiguous without any obstruction to the maximum extent of the area of the field.

Thus the embodiment of the invention makes possible an entirely free landing area with but a single observation structure if desired, that can be well in and even in the middle of the landing area, or near one side,—with all other equipment for housing and handling of planes, overhauling, etc., suitably provided for without any obstruction to flying. With such relative levels there is also the greatest insurance for complete drainage of the landing area proper. Where masses are to be handled on special occasions even the fences may be on a depressed border so as not to constitute an obstacle to leaving or approaching planes, with suitable mass ob-

servation areas thoroughly protected at a suitable distance from any portion of the field where regular flying occurs.

Different features of this port construction may be embodied in one or the other air terminals, or as sometimes called air-dromes or ports, and many of them may be in the same design, the salient features which provide the particularly advantageous features for safety and efficiency for operation and maintenance of flying stock fleets and regular schedule transport operations, are more particularly set forth in the claims.

While the particular embodiments herein shown and described may be varied greatly as to dimension, arrangement, combination, as well as coordination,—what I claim and desire to secure by Letters Patent is:

1. An airport comprising a substantially level area for aircraft operations and a sub-hangar having its roof substantially at the level of the main field, and means for ready access from the field to the sub-hangar floor for the transfer of aircraft comprising a structural area normally flush with the airport field and capable of depression to form a ramp registering with the sub-hangar floor.

2. An airport having its main aircraft operations field at one level and service buildings below the level of the field, with means of access to the service buildings below the field level including a ramp, and means for decking said ramp area flush with the airfield level.

3. In a system of airport equipment coordination comprising the landing field area, a control station extending slightly above the level of the field, hangar shop and storage space below the level with ramp means for ready transfer of flying stock from the field to the sub-storage space, and means to cover said ramp approach flush with the field area, and road or trackage below the field level having direct accessibility to the storage space floor and decking flush with the landing field area covering the roadway, sub-hangars and shops.

4. In an airport, a landing field at a predetermined elevation and having a generally level flush area for landing and departure of airplanes, operations control and observation station rising above the field level, goods or passenger station disposed slightly beyond the field area and having a lower story accessible from a road below the field level and an upper story accessible directly from the field level with its roof substantially on the same level or below the level of the observation structure roof.

5. A landing field for aircraft comprising a land area substantially level, and a contiguous flush area of deck and housing space below said deck to accommodate aircraft, access through said deck having an articulated closure to permit the entry or exit of aircraft

from the underground space and alternately to close said exit or entrance flush with the landing field area.

6. In an airport, aircraft landing and leaving area at a predetermined elevation generally level, goods or passenger accommodation facilities' construction below the landing area accessible by road transportation means under the level of and from the border of the landing area, means of access from said lower level structure to the landing area level including a ramp and means for decking said ramp area flush with the adjacent landing area.

15 7. An airport having its main aircraft landing and leaving area at one level, goods or passenger station structure disposed below the landing area level and a ramp for access therefrom to the landing area, and 20 means for decking the ramp area flush with the landing area.

8. An airport having a landing and leaving field area at a predetermined level, goods and passenger handling accommodations 25 structures below said level and means of access from the airport border to the under-level goods or passenger accommodating structures, said means of access being under the landing field level, a ramp interconnecting the sub-field level structure for access when desired to the landing area, and means for decking said ramp area flush with the adjacent landing and field surface.

9. An airport having aircraft landing and 25 leaving surface generally level at a predetermined elevation, structures for accommodating traffic built directly under the level of the landing field surface, with means of access from the substructures to the field level 40 including a ramp, means for covering the area occupied by said ramp to form a deck flush with the adjacent surface of the field area when the ramp is not in use, and railing or like means bordering the ramp area articulated to protect the opening when the ramp is in use, and adapted to lie flush with the flying surface when the ramp area is decked.

10. An airport having its main aircraft operations' field at one level, sub-level personnel and service accommodations below the level of the field, with means of access from the field level to the sub-surface accommodations including a ramp and means for decking the ramp area flush with the main operations' field surface, and a periscope or like means accessible from the sub-surface quarters having a range of vision over the adjacent surface, whereby the operation of the ramp connections may be controlled from 60 below with a clear vision of the movement of aircraft on the adjacent surface level.

11. In an airport, a landing and leaving field for aircraft having a predetermined level, sub-level structures for the accommodation of air traffic activities preliminary to

aircraft loading, a ramp connecting the sub-structure with the air field landing area surface comprising a counterbalanced structure having its upper surface flat and adapted to be swung into registration with the adjacent landing field surface, and means for locking the same whereby when the ramp area is closed the ramp constitutes a contiguous flush surface of the landing field adapted to support all loads of aircraft passing over the field.

Signed at New York, this 26th day of May 1928.
